UNITED STATES PATENT OFFICE.

JAMES F. LARGY, OF BARTON, VERMONT, ASSIGNOR TO CARL P. FORD AND CLARENCE H. WILLARD, A PARTNERSHIP, DOING BUSINESS AS J. W. MURKLAND COMPANY, OF BARTON, VERMONT.

AUTOMATIC SHELLACKING MACHINE.

Application filed May 18, 1922. Serial No. 562,010.

To all whom it may concern:

Be it known that I, JAMES F. LARGY, a subject of the King of Great Britain, and resident of Barton, in the county of Orleans and State of Vermont, have invented certain new and useful Improvements in Automatic Shellacking Machines, of which the following is a specification.

It is common practice to coat with shellac or similar substance spools, bobbins or similar devices to be used in connection with spinning or weaving since it is very desirable that they have a smooth surface. This operation is generally carried out by hand or by machines which require constant attention and manual performance of one or more steps.

An object of my invention is to provide a device for shellacking such objects which will be entirely automatic in its operation, the only prerequisite being that the magazine shall be supplied with the pieces to be coated.

Another object is to provide such a device in which the spool or bobbin shall be moved from the magazine upon a rotating spindle, coated by a brush, and automatically removed from the spindle at the termination of the coating operation.

Another object is to provide means whereby the brush is given a movement from end to end of the bobbin as the latter rotates, and back again, the brush being pressed with greater force against the bobbin during the return movement to wipe off the excess shellac.

Other objects will be apparent from the following detailed description and the appended claims.

In the drawings:

Figure 1 is a side elevation of the device. Figure 2 is a top plan view.

Figure 3 is an end elevation.

Figure 4 is a perspective view of the kicker-on or device for moving the bobbin on to the spindle, and the latch for normally restraining the same.

Figure 5 is a perspective view of a detail.

Figure 6 is a detail view, partly in section, showing the mechanism for operating the brush.

Figure 7 is a sectional view showing the kicker-on and latch.

Figure 8 is a perspective view of the brush operating mechanism.

The frame work of the machine may be of any desired type and is shown as comprising a top 1 supported on end pieces 2, each end piece having legs 3 and a lower cross connecting piece 4. Brackets 5 carried by the cross pieces 4 support bushings 6 in which is mounted a cam shaft 7. At one end this shaft has a pulley 8 about which passes a belt 9 communicating with any suitable source of power.

An extension 10 of the top 1 is provided with guides 11 in which slides a plate 12. Carried by this plate is an inclined magazine 13, the lower edge of which rests on the plate while the rear is supported by a standard 14 rising from the plate.

One side 15 of the magazine is fixed while the opposite side 16 is adjustable through bolt and slot connections 17 in order to adjust the magazine for different sizes of spools or bobbins.

Extending from one side of the magazine is an open framework composed of top 18, end 19 and bottom piece 20. This lower piece 20 extends across the lower edge of the magazine as shown in Figure 2 and provides an abutment against which the lowermost bobbin A rests. The sides 15 and 16, however, do not extend down to this piece 20, so that the lowermost bobbin may be moved endwise out of the magazine as hereinafter described.

Pivoted between ears 21 extending from the bottom of the plate 12 is a link 22 through which the plate and magazine are given intermittent reciprocating motion as will be set forth below. When the magazine is moved inward to one terminal position the lowermost bobbin is in line with a spindle 23 and is moved on to said spindle by the following mechanism.

A bar 24 slides in an opening in a bracket 25 attached to the end piece 19 and at its inner end is guided in the space between the lower end of the side bar 16 and the bottom piece 20. This bar is normally urged inward by a spring 26 attached at one end to the bar and at the other end to the frame piece 19.

The bar 24, sometimes termed the kicker-on is restrained from inward movement by a latch 27 pivoted on a pin 28 in an angle bracket 29 on the under side of the

magazine. As shown in Figure 4, this pawl has a tail 30 adapted to come into engagement with an angular member 31 fastened on the extension 10 of the top 1. The upturned end of the pawl, as clearly shown in Figures 4 and 7, lies between the sliding bar 24 and the lowermost bobbin A and prevents the bar from engaging the bobbin. As the magazine moves inward the tail 30 engages the piece 31 and is cammed upward drawing down the other end of the pawl, and when the magazine has reached the position where the lower bobbin is in line with the spindle 23, the pawl is moved to release the bar 24 which is moved quickly under the influence of the spring 26 and kicks the lower bobbin on to the spindle 23.

As the magazine then moves backward, it is necessary to withdraw the bar 24 so that the next bobbin may move down into position to be kicked on to the spindle at the next advance of the magazine. This is effected as follows.

Extending from the magazine 13 is an arm 32 to which is pivoted a bell crank lever 33, the long arm of which has a pin and slot connection with the bar 24 while the short arm has a pin 35 that works in a long slot 36 in a curved lever or link 37, the other end of which is pivoted at 38 to one of the guides 11. As the magazine and accompanying frame work moves inward, the pin 35 moves idly down the slot 36 causing the lever 37 to move about its pivot. As soon as the latch releases the bar 24 the spring 26 urges it endwise which movement results in rocking the bell crank 33 about its pivot and moving the pin 35 to the outer end of the slot 36. As the carriage and magazine again move back to the outer position, the pin 35 bearing against the end of the slot 36 constitutes substantially a fixed pivot for the bell crank 33, thereby causing the bell crank to turn about its own pivot on the arm 32 and moving the longer arm toward the right in Figures 1, 2 and 4, thus returning the bar 24 to the position shown in these figures. At the end of this movement, a spring 39 which bears against the tail 30 of the latching pawl, moves it into holding position.

The spindle 23 is mounted in a head stock 40 having a pulley 41 driven by a belt 42, and the head stock 40 is mounted in bearings supported on the top plate by legs or supports 44. The parts are so proportioned that the spindle and bobbin carried thereby are rapidly rotated. Mechanism 43 is provided for adjusting the spindle to correspond to different lengths of bobbins.

A pan or container 45 for the shellac or other substance employed is suitably supported on the top plate. Mounted to rotate and slide in bearings 46 attached to any appropriate part of the frame work is a

shaft 47 having an arm 48 adjustably mounted intermediate its ends, which arm supports a brush 49. The arm may be attached to the shaft in any desired manner and the brush may be clamped upon the arm as shown in Figure 8 or otherwise mounted thereon. Longitudinal movement is given the shaft through a link 50 pivoted to a collar 51 near one end of the shaft and having its other end pivoted to a lever 52 mounted on a pivot 53 carried by a bracket 54 depending from the top plate and actuated as hereinafter set forth. Rotary motion is given the shaft 47 by means of a downwardly extending cam arm 55 carried thereby and adapted to be actuated by a bar 56 carried by a lever 57 pivoted at 58 between ears 59 depending from the top plate, and actuated as hereinafter set forth.

After the bobbin has been shellacked it is kicked off the spindle 23 by the following means. A lever 60 is pivoted at 61 in a bracket 62 attached to the frame, and at its upper end is pivoted to a link 63 which in turn is pivoted at 64 to a collar 65 adjustably mounted on a rod or kick-off member 66 which slides in a guide 67 and is normally spring drawn in one direction by a spring 68. As shown in Figure 2, this kick-off member has a finger 69 at one end in a position to engage the bobbin A on the spindle. When the spring is allowed to move the member 66, this finger 69 kicks off the bobbin into any suitable receptacle. The spring is allowed to operate under conditions hereinafter recited.

All of the various instrumentalities are controlled and operated in sequence with proper timing through cams on the cam shaft 7. The lever 22 which controls the movement of the magazine, is pivoted intermediate its ends at 70 to an arm 71 carried by a collar 72 loose on the shaft 7, and at its lower end this lever 22 is pivoted at 73 to a link 74 having an elongated opening 75 embracing the shaft 7 and a roller 76 which works in a cam groove 77 in a cam 78 on said shaft. The cam groove is designed to give the desired movement to the magazine.

The lever 52 which controls the longitudinal movement of the brush carrying shaft 47 has a roller 79 at its lower end to engage a cam member 80. This lever is returned by a spring 81 attached to the lever and to the frame. The length of travel of this shaft 47 may be varied to correspond with the length of the bobbin by means of an adjustable collar 82 on the shaft 47 which will engage a bearing bracket 46 and stop the movement of the shaft lengthwise under the influence of the spring 81. For short bobbins the shaft will be stopped at a point where the roller 79 will not engage the cam 80 at all during a part of the rotation of the cam, but the cam will be designed to

allow the necessary movement for the longest bobbins that can be handled.

The lever 57 which controls the rotary movement of the brush carrying shaft 47 has a roller 83 at its lower end working in a cam groove 84 in a cam member 85 carried by the shaft 7. This cam groove will be designed so that on the return movement of the shaft 47 longitudinally the brush will be caused to bear harder on the bobbin and wipe off the excess of shellac.

The kick-off lever 60 has a roller 86 on its lower end adapted to drop into a depression 87 in a member 88 carried by the shaft 7 and permit the spring 68 to operate the lever and kick off the bobbin that has just been shellacked.

The operation of the device will be apparent from the above description but may be briefly recapitulated as follows:

The adjustable edge 16 of the magazine is set for the length of bobbin to be treated, the spindle 23 is correspondingly adjusted, and the adjustable collar 82 placed so as to give the proper degree of travel to the brush 49. The magazine is then filled with bobbins. The magazine is moved inward by cam operated lever 22 and when it reaches its limit of movement the latch 27 is tripped and the kicker-on 24 is actuated by spring 26 and moves the lowermost bobbin on to the spindle 23. The magazine immediately returns to original position and the kicker on is moved to its first position and held therein by the latch 27.

As soon as the bobbin is in place on the spindle 23, the cam 85 rocks the lever 57 and moves the member 56 giving the brush carrying shaft 47 a movement of rotation and bringing the brush against the bobbin. Then the cam 80 actuates the lever 52 and gives the brush carrying shaft 47 its sliding movement so that the brush will come in contact with all parts of the rapidly rotating bobbin. The spring 81 returns the shaft 47 and during the return movement the cam 85 causes the brush to bear with more force against the bobbin thus wiping off the surplus shellac.

When this movement is completed, the cam 88 has reached the point where the roller 86 will drop into the depression 87, permitting the spring 68 to actuate the kick-off 69 through the intermediate connections and kick off the shellacked spindle into any suitable receptacle. The cycle of operations is then repeated.

It is to be noted that many of the specific details are not essential to the spirit of the invention. The means for adjusting the size of the magazine, the position of the spindle, and the movement of the brush, the particular latching means for the kicker-on, and various other features, are to be considered as merely illustrative and not as limiting

the invention. The device is not limited in its application to bobbins or spools, and wherever these terms are employed they are to be understood as including any small pieces of suitable form having a hollow center that can be placed on a spindle. In general the scope of the invention is to be regarded as limited only by the appended claims.

I claim as my invention:

1. A shellacking machine comprising a magazine for bobbins, means for feeding bobbins one by one from the magazine on to a spindle, means for rotating said spindle, means for causing a brush to travel back and forth over the rotating bobbin, and means for removing the shellacked bobbin from said spindle.

2. A shellacking machine comprising a magazine for bobbins, a spindle rotating about its own axis, means for feeding the bobbins one by one on to said spindle, means for causing a brush to travel back and forth over the rotating bobbin, and means for removing the shellacked bobbin from the spindle, all of said means operating automatically and in proper sequence.

3. A shellacking machine comprising a magazine for bobbins, a spindle, spring actuated means for moving the bobbins one at a time on to said spindle, a latch for restraining the moving means, and automatic means for releasing the latch.

4. A shellacking machine comprising a magazine for bobbins, means for giving said magazine a reciprocatory movement, a spindle, spring actuated means for moving the bobbins one at a time on to said spindle, a latch for restraining the moving means, and automatic means operated by the movement of the magazine in one direction for releasing the latch.

5. A shellacking machine comprising a magazine for bobbins, means for giving the magazine a reciprocatory movement, a spindle, spring actuated means for moving the bobbins one at a time on to said spindle, a latch for restraining the moving means, automatic means operated by the movement of the magazine in one direction for releasing the latch, and means operated by the movement of the magazine in the other direction for restoring the moving means to original position.

6. A shellacking machine comprising a magazine for bobbins, means for giving the magazine a reciprocatory movement, spring actuated means for feeding the bobbins one by one from the magazine, a latch for restraining the moving means, and automatic means operated by the movement of the magazine in one direction for releasing said latch.

7. A shellacking machine comprising a magazine for bobbins, means permitting an

adjustment in the size of the magazine, a rotating spindle, means for varying the position thereof, means for feeding a bobbin from the magazine to the spindle, means for 5 feeding a brush over the surface of a bobbin on the spindle, and means for adjusting the degree of travel of the brush.

8. A shellacking machine comprising a magazine for bobbins, an adjustable side for 10 the magazine to permit the feeding of bobbins of different lengths, a spindle to receive a bobbin from the magazine, means for varying the position of the spindle to accommodate bobbins of different lengths, means for 15 feeding a bobbin from the magazine to the spindle, and means for giving a shellacking brush a variable travel to accord with the length of the bobbin being treated.

9. A shellacking machine comprising a 20 magazine for bobbins, a spindle for receiving a bobbin from the magazine, means for feeding a bobbin from the magazine to the spindle and means for moving a shellacking brush along the bobbin on the spindle, all of 25 said parts being adjustable to enable bobbins of different lengths to be treated.

10. A shellacking machine comprising a 30 constantly rotating spindle, automatic means for placing a bobbin thereon, a rocking and longitudinally movable shaft, means on said shaft supporting a brush, means for rocking said shaft to bring the brush in contact with the bobbin, and means for causing the shaft and the brush to travel to and fro lengthwise 35 of the bobbin.

11. A shellacking machine comprising a 40 constantly rotating spindle, automatic means for placing a bobbin thereon, a rocking and longitudinally movable shaft, a brush supported by said shaft, means for rocking the shaft to bring the brush in contact with the spindle, means for causing the brush and shaft to travel lengthwise of the bobbin, and means for varying the extent of said travel.

12. A shellacking machine comprising a 45 spindle, means for placing a bobbin thereon, a shaft, a brush supported thereby, means for rocking the shaft to bring the brush in contact with the bobbin, means for giving the shaft and brush a lengthwise movement, 50 and means for varying the extent of this movement.

13. A shellacking machine comprising a 55 spindle, means for placing a bobbin thereon, means for causing a brush to travel to and fro in contact with the bobbin, and means for causing the brush to bear with more force on the bobbin during the travel of the brush in one direction than in the other.

14. A shellacking machine comprising a 60 spindle, means for placing a bobbin thereon, cam means for causing a brush to travel lengthwise over the bobbin in one direction, spring means for causing the return movement of the brush, and means causing the 65 brush to bear with more force on the bobbin during the return movement.

15. A shellacking machine comprising a 70 spindle adapted to carry a bobbin, means for shellacking said bobbin while on said spindle, and means for automatically removing said bobbin from the spindle at the conclusion of the shellacking operation, said removing means being actuated in one direction by a spring and in the other direction 75 by a cam.

16. A shellacking machine comprising a 80 spindle rotating about its own axis, means for feeding a bobbin on to said spindle, means for causing a brush to travel longitudinally of the rotating bobbin over the whole length thereof, and means for removing the treated bobbin, all of said means being automatic.

In testimony whereof, I have hereunto 85 subscribed my name.

JAMES F. LARGY.
